CAMSHAFT GRINDING MACHINE

Clarence J. Green, Worcester, Mass., assignor to
 Norton Company, Worcester, Mass., a corpora-
 tion of Massachusetts

Application May 22, 1947, Serial No. 749,708

8 Claims. (Cl. 51—101)

1

This invention relates to grinding machines and more particularly to cam grinding machines.

One of the objects of this invention is to provide an apparatus and method whereby the deficiencies and disadvantages which accompany present methods of cam grinding, in which grinding occurs at large or wide variations in the surface speed of its elements relative to the grinding line between the cam and the grinding wheel, are relieved or overcome in a simple and effective manner.

Another object is to provide an apparatus for changing the angular velocity of a product cam at variable positions in its revolution in order to avoid excessive variations in the surface speed of the product cam relative to the grinding line. Another object is to provide a machine for varying the angular velocity of a product cam about its axis of rotation whereby the surface speed of its various elements relative to the grinding line is substantially uniform. Another object is to provide an apparatus for grinding a plurality of cam blanks on an integral camshaft at substantially uniform work surface speeds at the grinding line. Another object of this invention is to provide a simple and thoroughly practical apparatus for grinding a plurality of cam blanks on an integral camshaft.

Another object is to provide for the control of the rotation of a product cam that is being ground by a grinding wheel so as to achieve substantially uniform surface speed of all of the elements of the product cam relative to or at the grinding line even though such elements or portions thereof are of widely varying radii. Another object is to provide means in a grinding machine for generating a cam surface on a cam blank at a substantially uniform grinding surface speed over all of the portions of the cam surface.

Another object of the invention is to provide means for indexing an apparatus or control for changing the speed of rotation of each of a succession of product cams on a camshaft.

Another object of the invention is to provide means for automatically indexing work speed control apparatus in timed relation with indexing of cam blanks being ground. Another object is to finish grind a cam more accurately. Another object is to obtain an improved grinding action on certain portions of a product cam. Another object of the invention is to accelerate the production of ground camshafts. Another object is to achieve better and uniform grinding action on a cam periphery even though elements or portions of the peripheral cam surface are of different radii.

2

Other objects will be in part obvious or in part pointed out hereinafter. The invention accordingly consists in the features of construction, combinations of elements and arrangements of parts, as will be exemplified in the structure to be hereinafter described, and the scope of the application of which will be indicated in the following claims.

In the accompanying drawings, in which is shown one of the various possible embodiments of the mechanical features of this invention,

Figure 1 is a view partly in plan and partly in section showing the work table of a cam grinding machine, the rock bar, the master cam shaft, the work centers, the work driving mechanism and the mechanism of the present invention.

Figure 2 is an elevation of the indexing mechanism both for the master cam roller and for the electrical contact mechanism of the invention, the view being taken in the direction of the arrows 2—2 of Figure 1.

Figure 3 is a vertical sectional view, on an enlarged scale, taken along the line 3—3 of Figure 1.

Figure 4 is a vertical sectional view taken along the line 4—4 of Figure 2.

Figure 5 is a sectional view taken along the line 5—5 of Figure 3.

Figure 6 is a sectional view taken along the line 6—6 of Figure 3.

Figure 7 is a view partly in side elevation and partly in section of the contact device of the invention together with a wiring diagram.

Figure 8 is a diagram illustrating a cam grinding cycle.

As conducive to a clearer understanding of this invention it may at this point be noted that peripheral cams are made in widely varying shapes and that according to known practices of grinding their cam surfaces, namely, by simply rotating the cam about its axis at a given R. P. M. to thereby present the cam surface to the grinding wheel, many disadvantages, deficiencies, and detrimental actions and results occur. In general, the surface of a cam may be said to be irregular even though some regular pattern of shape or curvature may be present. A simple form of cam may have a nose, flanks and a base, and I have in Figure 8 selected such a simple form of cam for purposes of illustration. The surface elements of the cam in each of the portions lie at various radial distance from the center or axis of rotation of the cam.

When the irregular surface of a cam is generated in grinding a cam blank according to known practices, the cam is rotated about its axis at fixed or constant speed and as a result, the sur-

face speeds of the various portions of the cam, as they are successively presented to the grinding wheel, vary widely relative to the grinding line, the line of contact between the grinding wheel and the cam. Thus, when the cam turns at a constant angular velocity, the flanks of the cam sweep past the grinding line at a much faster speed than the nose, and the base moves at an intermediate speed in surface feet per minute.

This varying surface speed of the nose, flanks and base of the cam relative to the grinding line for a constant turning speed of the cam in revolutions per minute is graphically illustrated in Figure 8, where a typical cam 20 and a grinding wheel having a grinding surface 21 are shown in various relative positions in mutual contact at a grinding line as the cam is revolved relative to the wheel to grind it. The illustrative cam 20 has a major center O through which the axis of its revolution passes, a base 23 with a radius of one inch about the center O, straight flanks 24 and 25 each seven-eighths of an inch in surface length, and a nose 26 with a radius of one-half inch about a minor center 26a which is materially displaced from the cam axis. The surfaces of the flanks 24 and 25 are tangent to the surfaces of the base 23 and the nose 26.

To grind the flank 24, the cam 20 and grinding wheel 21 may be brought in contact to form a grinding line at 27 with the grinding wheel center at 28 relative to the cam 20. As the cam is rotated counterclockwise, the grinding line moves along the flank 24 seven-eighths of an inch to grind the flank whereupon the grinding line is now at 29 and the relative position of the wheel center is at 30. This change in relative positions of cam and wheel is effected by cam rotation about the center O through the angle AOB which is 16 degrees to grind the flank 24. During cam rotation to grind the flank the grinding line moves from 27 to 29, a surface distance of .054 inch per degree of cam rotation.

To grind the nose 26 the cam continues to rotate counterclockwise about its center 26a so that the grinding line moves along the surface of the nose 26 to 31, a distance of 1.08 inches, the wheel center now being at 32. This change in relative positions of cam and wheel is effected by cam rotation about the center O through the angle BOC which is a cam rotation of 92 degrees to grind the nose 26. During cam rotation to grind the nose the grinding line moved along the nose surface from 29 to 31 a surface distance of .011 inch per degree of cam rotation, as compared to .054 inch per degree for the flank. To grind the flank 25 the cam continues to rotate counterclockwise through the angle COD about its center O causing the grinding line to move along the flank 25 at a rate of .054 inch per degree of cam rotation. The grinding line is now at 33 and the wheel center at 34.

To grind the base 23 the cam moves counterclockwise about its center O and the grinding line moves from 33 to 27, the wheel center now being at 28 where it started. This change in relative cam and wheel positions is effected by cam rotation about the center O through the large angle DOA which is a cam rotation of 236 degrees to grind the base. During cam rotation to grind the base the grinding line moved relative to the base 23 from 33 to 27, at a rate of .017 inch per degree of cam rotation. The ratio of the surface speeds for the flanks, nose and base of this cam for any constant angular velocity is therefore 54:11:17.

Assuming that the cam of the illustration is

rotated at twenty revolutions per minute, the grinding line moves, relative to the nose surface at a surface speed of 79.2 inches per minute, relative to the base surface at a surface speed of 122.4 inches per minute, and relative to the flanks at a surface speed of 388.8 inches per minute.

The disadvantages of grinding at these tremendously varying work surface speeds as has been the past practice are readily apparent when

10 it is pointed out that the rate at which the grinding wheel may be fed into the work depends directly upon the surface speed of the revolving work piece relative to the grinding line, and the rate of wheel feed into the work governs the 15 time of the overall grinding operation. For a given operation, it is desirable that the rates of wheel infeed and work surface speed bear certain 20 relations and they are established in order to obtain the most efficient work removal. However, 25 to grind a cam, which always has a number of different surface speeds for a constant angular velocity, the maximum constant angular velocity which can be given the cam is the one which will give the work surface speed required at the 30 grinding line for that portion of the cam which has the greatest surface speed for any given angular velocity. Then the other portions of the cam have surface speeds at the grinding line which are too slow for efficient grinding operation. 35 For the cam illustratively dimensioned as above, it was shown above that at twenty revolutions per minute the surface speed of the flank is 388.8 inches per minute. If this is established as an efficient work surface speed at which to 40 grind the cam for a given rate of wheel infeed, then the resulting surface speeds of 79.2 inches per minute for the nose and 122.4 inches per minute for the base are not efficient work surface speeds for grinding these parts. The finish produced around the cam is not uniform, resulting in the necessity of further lapping and finishing operations. Considerable time is wasted in turning the work too slowly for certain portions of the 45 cam because the grinding wheel is not removing as much material as it efficiently could on those portions of the cam.

Referring now to Figure 1, the machine illustrated is a cam grinder for grinding the many cams on an automotive cam shaft. The present 50 invention is fully applicable to an automatic cam grinder in which the work table 50 is automatically moved from station to station successively to cause the grinding wheel 21a to grind the cams 20a, 20b, 20c, 20d, 20e, 20f, 20g and 20h. 55 Before such movements, known as indexing, the rock bar 52 of the machine is swung to move the cam shaft 53 having the cams 20a, 20b, etc. away from the grinding wheel 21a and at the same time to move the master cam shaft 54 away from the 60 master cam roller 55; coincidentally the grinding wheel 21a is retracted so that it can be advanced in feeding components to grind the next cam such as 20b. The table traversing mechanism of an automatic cam grinder, the wheel retracting 65 and feeding mechanism of such grinder, and the fluid connections to cause the rock bar 52 to swing away are now well known in this art and therefore will not be described herein. For an understanding thereof reference may be had to 70 U. S. patent to Belden and Silven, No. 2,022,178 and U. S. patent to Silven, No. 2,078,463. There will be described herein only so much of the structure of such old automatic cam grinder as will suffice to show the connection of the invention therewith.

Referring now to Figure 3, the table or carriage 50 has a flat way 60 and V-ways 61 which rest on a flat way 62 and V-ways 63 provided by the base 64 of the machine. Referring to Figure 1, near the left hand end of the carriage 50 is shown a bearing box 66 which is fastened to the carriage 50 and journals one end of the rock bar 52; the other end of the rock bar 52 is beyond the right hand end of Figure 1 but in Figure 3 a similar journal box 67 is shown, which is likewise fastened to the carriage 50, and which journals the right hand or far end of the rock bar 52, a trunnion portion 68 of which is located in said journal box 67 and is shown in Figure 3 in dotted lines.

The rock bar 52 has upstanding portions 70, 71 and 72 which house bearings 73, 74 and 75 journaling the master cam shaft 54. Previous cam grinders have had master cam shafts but this master cam shaft 54 is of extra length to support not only the master cams 80a, 80b, 80c, 80d, 80e, 80f, 80g, and 80h but also a set of control cams 90a, 90b, 90c, 90d, 90e, 90f, 90g and 90h. These control cams 90a to 90h are part of the mechanism of the present invention.

The cams 80a, 80b, etc. are master cams to generate the shapes of the product cams 20a, 20b, etc. The master cams 80a, 80b, etc. are keyed to the cam shaft 54 and held between an enlarged portion 91 of the cam shaft 54 and a sleeve 92 on said shaft which is held in position by a nut 93 on a threaded portion 94 of the master cam shaft 54. The control cams 90a, etc. are likewise keyed to the cam shaft 54 and are held between a shoulder 95 and a sleeve 97 backed up by a nut 98 on the threaded portion 99 of the cam shaft 54. This cam shaft 54 is connected to a universal joint 100 which is connected by a shaft 101 to another universal joint 102 which is connected to a shaft 103 mounted in a bearing housing 104 fastened to the table 50, the shaft 103 having mounted on its left hand end a pulley 105 which is connected by belts 106 to pulley 107 driven by an electric motor 108 through a reduction gearing in a casing 109. A master cam shaft is thus rotated at a speed determined by the speed of the motor 108 and the drive is continuous despite the fact that the master cam shaft 54 oscillates about the center of oscillation of the rock bar 52.

The master cam shaft 54 is also a work drive shaft. Still referring to Figure 1, adjacent the right hand bearing 75 is an enlarged portion 111 of the master cam shaft 54 which operates as a thrust member. The master cam shaft 54 has a conical axial hole, not shown, in its right hand end which received a work holding "center" 113 which centers the cam shaft 53; the other end of the cam shaft 53 is centered by a "tail center" 114 held by a tail stock 115, that is adjustably fastened to the rock bar 52. Thus the work piece cam shaft 53 is held for rotation in line with the master cam shaft 54 and it is rotated through a driving dog 116 which has a pin 117 entering a slot in a driving head 118 fastened to the right hand end of the master cam shaft 54.

At any time during actual grinding the master cam roller 55 is in contact with one of the master cams. It is shown as being in contact with master cam 80a while the grinding wheel 21a is grinding the product cam 20a. The roller 55 can rotate and it is indexed from time to time to place it adjacent the various cams 80a, 80b, 80c, etc., and likewise it is carried by the table 50, but otherwise it does not move. Thus it is the rotation of a master cam such as 80a in con-

tact with the master cam roller 55 which oscillates the master cam shaft 54 on the pivotal center of the rock bar 52, the tail center 114 as well as the head center 113 likewise oscillating. This is what generates the desired shape on the product cams 20a, 20b, etc.

When the product cam 20a has been ground, the machine by mechanism not herein described, causes the table or carriage 50 to move to place the product cam 20b in front of the grinding wheel 21a. Just prior to this movement the rock bar 52 is swung to move the product cam shaft 53 away from the grinding wheel 21a and to move the master cams away from the master cam roller 55. This motion of the table or carriage 50 automatically causes the master cam roller 55 to be moved opposite to the next master cam 80b, and this mechanism will now be described.

Referring now to Figure 1, the table or carriage 50 has an upwardly extending support 125 which has the shape of a rectangular parallelopiped. In Figure 1 the upper frame portions and mechanisms have been omitted for the sake of clarity; if they were shown the master cam shaft 54 and the various master cams 80a, 80b, etc. and 90a, 90b, etc. and also other parts would be obscured. The support 125 has a number of tapped holes 126 by means of which an over arm 127 is bolted to the support 125. As shown in Figure 3 this over arm 127 extends over the top of the rock bar 52 and over the master cam shaft 54 and as will be seen by a comparison of Figures 2 and 3 the over arm 127 has a flat horizontal portion 128 forming a complete cover for the cams 80a, 80b, etc., the horizontal portion 128 being connected to large ribs 129 and 130 in parallel vertical planes which extend well above the horizontal portion 128 and which ribs 129 and 130 merge into downwardly extending arms 131 and 132 at the rear side of the table 50.

Still referring to Figure 2, extending horizontally from the right hand side of the arm 132 is an integral portion 133 which, as best shown in Figure 3 is T-shaped in cross section. The downwardly extending arm 131 supports a journal 135, the downwardly extending arm 132 supports a journal 136 (Figure 4) and a downwardly extending arm 137 on the end of the portion 133 supports a journal 138. These journals 135, 136 and 138 as best shown in Figure 1 support a shaft 140 upon which the master cam roller 55 is mounted. While the shaft 140 could be a non-rotatable shaft it has been found preferable to key the roller 55 to it as by means of a long key 142 so that the shaft 140 rotates in journals which are widely separated.

Referring now to Figure 1, fastened to and extending rearwardly from the base 64 is an arm 145 on the end of which is a bracket 146 holding and supporting a pair of bars 147, 147. Referring to Figures 1, 2 and 3, at the lower ends of the downwardly extending arms 131, 132 and 137 are sliding supports 150, 151 and 152 respectively which move with the table or carriage 50 but at all times support the bars 147 from sagging. Supported by the bars 147 are dogs 155 secured in adjusted positions by means of screws 156. These dogs 155 should be spaced the same as the spacing of the product cams 20a, 20b, 20c, etc. Since the bars 147 are held by the arm 145 secured to the base 64, the dogs 155 do not move; as the table or carriage 50 moves from one position to another a dog 155 is engaged by a star 75 wheel 158 which moves with the table or car-

riage 50. Each such engagement therefore rotates the star wheel 158 through a unit angle.

As shown in Figures 3 and 4, the star wheel 158 is integral with a sleeve 160 which is journalled on a stud 161 secured to the downwardly extending arm 132. Secured to the sleeve 160 is a gear 163 which meshes with an adjustable gear 164 mounted as shown in Figures 1, 2 and 4, on a stud 165 integral with a bar 166 that is adjustably secured by a bolt 167 to a slideway member 170, see Figures 1, 2, 3 and 4. The bar 166 has a long slot 171 therein through which the bolt 167 passes, in order to adjust the position of the gear 164.

The gear 164 meshes with a gear 175 which, as best shown in Figure 4 is integral with a sleeve 176 mounted on a stud 177 that is secured to the downwardly extending arm 132. Likewise integral with the sleeve 176 are gears 178 and 179; the gear 178 meshes with a rack 180 slidably mounted in a slideway in the slideway member 170, while the gear 179 meshes with a rack 182 also slidably mounted in a slideway in the slideway member 170. The gear 178 is larger than the gear 179, and to compensate for this the rack 182 is higher than the rack 180; it is clear that whenever the star wheel 158 is turned through a unit angle, both of the racks 180 and 182 will be moved, but the former will be moved a greater distance than the latter. The rack 180, when thus moved, moves the master cam roller 55 along the shaft 140, by means of connections to be described. The rack 182, when moved, moves electrical control mechanism to be described with respect to the control cams 90a, 90b, etc. The slideway member 170 is fastened to the downwardly extending arms 131, 132 and 137 and therefor partakes of the motion of the table or carriage 50.

Referring now to Figure 1 in connection with Figure 4, a yoke member 190 straddles the roller 55 and rests upon the hub 191 thereof and encircles the hub half way as shown in Figure 4. A semi-circular portion of the yoke member 190 is on each side of the roller 55 and thus the roller 55 is moved whenever the yoke member is moved parallel to the shaft 140. A rearwardly extending portion 195 of the yoke member 190 has a depending portion 196 which is secured to the rack 180 which, as shown, can move only parallel to the shaft 140. Thus indexing movements of the rack 180 responsive to actuation of the star wheel 158 cause indexing movements of the cam roller 55.

Referring now to Figures 1 and 3, attached to the rack 182 is a rearwardly extending portion 199 of a yoke 200 which extends half way around the shaft 140 between the bearings 136 and 138. This yoke 200 is therefore moved along the shaft 140 whenever the star wheel 158 is turned through a unit angle. Such movement, being step by step in response to step by step motion of the table 50, is referred to as indexing and it will be noted that the yoke 200 is indexed shorter distances than the yoke 190 due to the difference in diameter between the gears 178 and 179, thus to allow for the closer packing of the cams 90a, 90b, etc., than that of the cams 80a, 80b, etc.

The yoke 200 has a pair of depending parallel portions 201 between which at all times is a finger 202 extending rearwardly from the hub 203 of an arm 205. The hub 203 is keyed to a trunnion shaft 210 by means of a key 211, Figure 5, and the shaft 210 as shown in Figures 3 and 5 is mounted in bearings 212 and 213 in integral arms 214 and 215 extending rearwardly from the rock bar 52.

Thus whenever the rack 182 moves, the yoke 200 must move with it and, since the finger 202 is always between the depending portions 201 of the yoke 200, and since the finger 202 is integral with the hub 203 of the arm 205, the arm 205 will be moved whenever the rack 182 is moved. Thus the arm 205 is indexed from control cam to control cam, e. g. from cam 90a to cam 90b and then from cam 90b to cam 90c and so forth.

10 Referring now to Figure 5 and noting the section line for this figure on Figure 3, the shaft 210 has on one end a holding collar 216 and on the other end a hub 218 with a split arm 220, the hub 218 being keyed to the shaft 210 by means of a key 221. The collar 216 and the hub 218 keep the shaft 210 from moving axially. Referring to Figures 3 and 5 a long bolt 225 extends through the rock bar 52 and through the split arm 220 and acts an adjustable limiting stop to prevent the arm 205 from moving clockwise, Figure 3, relative to the bearings 212 and 213 in which its trunnion shaft is journalled. A nut 226 on one end of the bolt 225 and a pair of nuts 227 on the other end thereof set the adjustable limit while a spring 228 on the bolt 225 resiliently keeps the arm 205 at the limit angularly.

During the grinding operation a master cam such as the cam 80a stays in contact with the master cam roller 55. Therefore the rock bar 52 oscillates. The force which keeps the master cam such as 80a in contact with the master cam roller 55 is derived from a spring 230 (Figure 3) in a cylinder 231, the spring exerting its force against a piston 232 in the cylinder 231, the piston 232 being attached to a piston rod 233 which extends outside of the cylinder 231 and has on the end thereof a clevis 234 by means of which it is pivotally attached to an arm 235 which is integral with the rock bar 52. The cylinder 231 is positioned by means of a split collar 236 which is pivotally mounted on the overarm 127 so that it can swing to accommodate the slight angular motion of the piston rod 233. Whenever the table 50 is about to be indexed, fluid is admitted to the upper side of the piston 232 in the cylinder 231 which rocks the rock bar 52 carrying the cams 80a, 80b, etc., away from the master cam roller 55 so that the master cam roller can be indexed without hitting one of the cams on the side. The means for causing fluid to be admitted to the cylinder 231 at such stages is no part of the present invention having been described in the aforesaid patents and being otherwise known to the art.

55 This rocking of the rock bar 52 to carry the cams 80a, etc. well away from the master cam roller 55 likewise causes the arm 205 to move relative to its assembly on the rock bar 52. The finger 202 strikes the shaft 140 and this swings the arm 205 counter clockwise relative to the rock bar 52, compressing the spring 228. Of course it will be seen that since the rock bar is moved clockwise (Figure 3) it is really the rock bar and associated parts which move away from the arm 205, but relatively speaking the arm 205 moves counter clockwise. At other times the arm 205 has a fixed angular relation to the rock bar 52 and the parts assembled thereon. This relative counter clockwise movement of the arm 205 permits said arm and the electrical mechanism associated therewith to be indexed from one cam 90 to another cam 90 without interference.

60 The arm 205 carries electrical contact mechanism which controls the speed of the motor 108. Referring now to Figure 7, the arm 205 has a pair of rigid parallel projections 240 and 241.

Through the projection 240 is a bore 242 in which is slidably mounted a rod 243 having a narrow contact portion 244 which can engage any one of the cams 90a, 90b, etc. The rod 243 is keyed by means of a key 245 to the rigid parallel projection 240 so that the narrow contact portion will not get out of alignment. The rod 243 has an enlargement 248 between which and the rigid parallel projection 240 extends a spring 249. It will now be seen that as a cam 90 rotates it moves the rod 243 to different positions relative to the projection 240 and the projection 241.

Still referring to Figure 7, at the left hand end of the rod 243 is a screw threaded portion 250 upon which is screwed an insulating sleeve 251 and firmly located in a bore 252 of a metal cap 253. Around the cap 253 is a metal collar 254 having an integral contact arm 255. Into the collar 254 is screwed a binding post screw 256 on which is a terminal member 257 between binding post nuts 258. The terminal member 257 is on the end of a wire 260.

The arm 255 makes and breaks contact with a long binding post screw 261 on which is a terminal member 262 between binding post nuts 263. This binding post screw 261 is adjustably positioned in a threaded sleeve 265 by means of a nut 266. The threaded sleeve 265 has an integral ring 267 which locks it to an integral insulating sleeve 268 which is molded around the sleeve 265 which may be made of metal. The insulating sleeve 268 is secured in the projection 240 by means of externally threaded rings 270 screwed into a threaded bore 271 in the projection 240.

The motor 108 is a variable speed motor, for example it can be a direct current motor. It is represented in Figure 7 as having two brushes 275 and 276. The brush 275 is connected to a main power line 277. The brush 276 is connected by a line 278 to a rheostat coil 280. A movable rheostat contact 281 is connected to a wire 282 on the end of which is the terminal member 262. The wire 260 is connected to a hand switch 283 which is used to stop and start the motor 108. The other side of the hand switch 283 is connected to the other main power line 285. Thus when the arm 255 is in contact with the binding post screw 261, the motor 108 will run at a speed determined by the position of the movable rheostat contact 281.

The cap 253 has a terminal point 287 which can contact a terminal point 288 of a metal rod 289 which is slidably in an insulating sleeve 290 molded inside of a metal sleeve 291 which has an interlocking ring portion 292. The metal sleeve 291 is externally threaded and screwed into a threaded bore 294 in the rigid parallel projection 241. A nut 295 on the threaded sleeve 291 adjustably secures the latter in the projection 241. The rod 289 has an enlarged portion 299 and a spring 300 on the rod 289 extends between the enlarged portion 299 and the insulating sleeve 290. The rod 289 on the left hand end has a threaded binding post portion 301 on which is a terminal member 302 between nuts 303 and 304. The spring 300 urges the rod 289 to the right to a position determined by the nut 304 and of course the nuts 303 and 304 can be adjusted thus to adjust the normal position of the rod 289 in the sleeve 290 and furthermore the position of the sleeve 290 can be adjusted by loosening the nut 295, turning the sleeve 291 and then re-tightening the nut 295. The terminal member 302 is on the end of a wire 306 which is connected to a movable rheostat contact 307. It will now be seen that

when the terminal point 287 is in contact with the terminal point 288, the motor 108 will run at a speed dependent upon the position of the movable rheostat contact 307. It will further be seen that when the point 287 has contacted the point 288 further movement to the left of the point 287 will not break anything but will simply crush the spring 300.

I provide a third movable rheostat contact 310 connected by a wire 311 to a junction 312 with the wire 260. When the arm 255 is not in contact with the binding post screw 261 and the point 287 is not in contact with the point 288, the motor 108 will run at a speed determined by the movable rheostat contact 310. Thus three speeds are established for the motor 108 and each of them can be easily adjusted.

All of the cams 90 have a base portion 90x, flank portions 90y and a nose 90z. The adjustable electric contact mechanism is set so that when the contact portion 244 is opposite the base 90x, there will be a slight clearance and therefore the arm 255 will be in contact with the binding post 261. But when a flank 90y is adjacent the contact portion 244, the rod 243 is positioned to the left breaking contact between the arm 255 and the binding post 261. Furthermore contact between the points 287 and 288 is made and kept while the contact portion 244 is in engagement with any part of the nose 90z.

It will now be seen that the product cam shaft 53 will be rotated at different angular velocities during each revolution, that is to say at one angular velocity when the base 23 of a cam 20 is in contact with the grinding wheel 21a, at another angular velocity when either of the flanks 24 or 25 is in contact with the grinding wheel 21a, and at a third angular velocity when the nose 26 is in contact with the grinding wheel 21a. The base 90x of the cams 90 should displace the same angle as the base 23 of the corresponding cam 20 and similarly for the flanks and the nose. Because of the fact that the armature of the motor 108 and all the other moving parts have inertia, the cams 90 should be timed a little ahead of the product cams 20. This advance in timing can be arbitrarily set at about 4° with good practical results. If, as is sometimes the case, the various cams 20 differ considerably from each other, the machine nevertheless will perform accurately because the cams 90 can be made correspondingly different.

The movable rheostat contacts 281, 307 and 310 should be set to give constant surface speeds for the flanks, nose and base of the product cams 20 relative to the grinding line, and may readily be so set as will now be apparent. The circuit through the wire 310 will generally be adjusted to have the greatest resistance and thus when either of the other circuits is closed it will control the speed. Adjustment can readily be made of the contacts 281 and 307 to allow for the fact that some current will flow through the circuit including the wire 311 which has the highest resistance. All adjustments can be made by the application of Ohm's law and mathematics.

The drawings show a resistance coil 280 but this is merely because it is conventional in patent drawings and a bar resistor can be used or any other device to vary the speed of the motor 108 can be used. The motor 108 can be any type of variable speed electric motor, not necessarily a direct current motor.

It will thus be seen that there has been provided by this invention apparatus in which the

11

various objects hereinabove set forth together with many thoroughly practical advantages are successfully achieved. As many possible embodiments may be made of the above invention and as many changes might be made in the embodiment above set forth, it is to be understood that all matter hereinabove set forth or shown in the accompanying drawings is to be interpreted as illustrative and not in a limiting sense.

I claim:

1. In a cam grinder, the combination with a table or carriage, journals for a rock bar on said table or carriage, a rock bar in said journals whereby said rock bar can be oscillated on an axis extending through said journals, work centering and driving mechanism on said rock bar located away from said axis whereby as the rock bar oscillates the work centering and driving mechanism will move through an arc, a master cam shaft having a plurality of master cams mounted for rotation on said rock bar also away from said axis, a master cam roller mounted on said table or carriage adjacent the master cam shaft whereby it can contact one (at a given time) master cam to control the oscillations of said rock bar, means exerting a force on said rock bar to keep the master cam in contact with the master cam roller, means to index said master cam roller from one master cam to another one, and power means connected synchronously to drive the work driving mechanism and the master cam shaft, of a control cam shaft journaled for rotation on said rock bar having a plurality of control cams thereon, connections to the power means to drive the control cam shaft synchronously with the work driving mechanism and the master cam shaft, make and break electrical contacts mounted on said rock bar and having a part to be moved by one (at a given time) of said control cams, means for moving said make and break electrical contacts away from said control shaft to permit indexing, means mounting said make and break electrical contacts for indexing from one to another of said control cams, and means to effect said indexing of said make and break electrical contacts when they are moved away from said control shaft.

2. In a cam grinder as claimed in claim 1, the combination with the parts and features therein specified, of a shaft on the rock bar parallel to the axis of the rock bar, said make and break electrical contacts being mounted on said shaft on the rock bar whereby they can be swung away from the control cam shaft on said shaft on the rock bar as a pivot and can be slid on said shaft on the rock bar to index from one control cam to another.

3. In a cam grinder as claimed in claim 2, the combination with the parts and features therein specified, of an arm and connections for swinging the make and break electrical contacts on the shaft on the rock bar responsive to an oscillation of the rock bar.

4. In a cam grinder the combination with a table or carriage, journals for a rock bar on said table or carriage, a rock bar in said journals, whereby said rock bar can be oscillated on an axis extending through said journals, work centering and driving mechanism on said rock bar located away from said axis whereby as the rock bar oscillates the work centering and driving mechanism will move through an arc, a master camshaft having a plurality of master cams mounted for rotation on said rock bar also away from said axis, a master cam roller mounted on

12

said table or carriage adjacent the master cam-shaft whereby it can contact one (at a given time) master cam to control the oscillations of said rock bar, means exerting a force on said rock bar to keep the master cam in contact with the master cam roller, means to index said master cam roller from one master cam to another one, and an electric motor connected synchronously to drive the working driving mechanism and the master cam-shaft, of a control camshaft having a plurality of control cams thereon, an operative connection between said control camshaft and said electric motor whereby said control camshaft is rotated synchronously with the master camshaft and the work driving mechanism, control mechanism including a variable impedance to change the rate at which said electric motor rotates the work driving mechanism the master camshaft and the control camshaft, part of said control mechanism being positioned to be operated by one (at a given time) of said control cams, whereby said work driving mechanism will have at least two speeds during a single revolution thereof, and means to index said part of said control mechanism from one control cam to another control cam, said two indexing means being synchronized.

5. In a cam grinder as claimed in claim 4, the combination with the parts and features therein specified, of the further feature that the control mechanism also includes make and break electrical contacts.

6. In a cam grinder as claimed in claim 5, the combination with the parts and features therein specified, of means for swinging said part of said control mechanism away from a control cam just prior to the indexing and to return it to the new control cam when the indexing is accomplished.

7. In a cam grinder the combination with a table or carriage, journals for a rock bar on said table or carriage, a rock bar in said journals whereby said rock bar can be oscillated on an axis extending through said journals, work centering and driving mechanism on said rock bar located away from said axis whereby as the rock bar oscillates the work centering and driving mechanism will move through an arc, a master cam shaft having a plurality of master cams mounted for rotation on said rock bar also away from said axis, a master cam roller mounted on said table or carriage adjacent the master cam shaft whereby it can contact one (at a given time) master cam to control the oscillations of said rock bar, means exerting a force on said rock bar to keep the master cam in contact with the master cam roller, means to index said master cam roller from one master cam to another one, and power means connected synchronously to drive the work driving mechanism and the master cam shaft, of a control cam shaft having a plurality of control cams thereon, an operative connection between said control cam shaft and said power means whereby said control cam shaft is rotated synchronously with the master cam shaft and the work driving mechanism, control mechanism to change the rate at which said power means rotates the work driving mechanism the master cam shaft and the control cam shaft, part of said control mechanism being positioned to be operated by one (at a given time) of said control cams,

whereby said work driving mechanism will have at least two speeds during a single revolution thereof, means to index said part of said control mechanism from one control cam to another control cam, said two indexing means being synchronized, and means for swinging said part of

13

said control mechanism away from a control cam just prior to the indexing and to return it to the new control cam when the indexing is accomplished.

8. In a cam grinder the combination with a table or carriage, journals for a rock bar on said table or carriage, a rock bar in said journals whereby said rock bar can be oscillated on an axis extending through said journals, work centering and driving mechanism on said rock bar located away from said axis whereby as the rock bar oscillates the work centering and driving mechanism will move through an arc, a master cam shaft having a plurality of master cams mounted for rotation on said rock bar also away from said axis, a master cam roller mounted on said table or carriage adjacent the master cam shaft whereby it can contact one (at a given time) master cam to control the oscillations of said rock bar, means exerting a force on said rock bar to keep the master cam in contact with the master cam roller, means to index said master cam roller from one master cam to another one, and an electric motor connected synchronously to drive the work driving mechanism and the master cam shaft, of a control cam shaft having a plurality of control cams thereon, an operative connection between said control cam shaft and said electric motor whereby said control cam shaft is rotated synchronously with the master cam shaft and the work driving mechanism, control mechanism in-

14

cluding a variable impedance to change the rate at which said electric motor rotates the work driving mechanism the master cam shaft and the control cam shaft, part of said control mechanism being positioned to be operated by one (at a given time) of said control cams, whereby said work driving mechanism will have at least two speeds during a single revolution thereof, means to index said part of said control mechanism from one control cam to another control cam, said two indexing means being synchronized, and means for swinging said part of said control mechanism away from a control cam just prior to the indexing and to return it to the new control cam when the indexing is accomplished.
